THOMAS KELLEY, OF PROVIDENCE, RHODE ISLAND, ASSIGNOR TO CROMPTON & KNOWLES LOOM WORKS, OF WORCESTER, MASSACHUSETTS, A CORPORATION OF MASSACHUSETTS.

NEEDLE FOR JACQUARD.

Application filed January 10, 1927. Serial No. 160,120.

This invention relates to improvements in jacquard mechanisms for looms and it is the general object of the invention to provide a form of jacquard needle which will insure accurate movement of the warp controlling hooks and at the same time permit a large number of needles to be housed in a relatively small space.

Jacquard mechanisms are provided with a series of needles which are usually moved horizontally by cards and cooperate with warp lifting jacks or hooks which are reciprocated vertically by knives or griffes. Each needle controls the horizontal position of one of the jacks, this control usually being effected by a crimp or eye in the needle which partly or completely surrounds the jack. I find that when the eyes are entirely closed the hooks can not be tested as closely as is necessary for fine index work, and I furthermore find that when the crimp or eye is of the usual open type the hook is engaged by the rounded part of the open eye and deflected laterally with resultant improper action. It is an important object of my present invention to provide a needle having a partly closed eye so formed as to restrain improper movement of the hook or jack, but at the same time permit close assembling of the hooks.

With these and other objects which will appear as the description proceeds, my invention relates to the arrangement and combinations of parts hereinafter set forth, and more particularly pointed out in the claims.

In the accompanying drawings, wherein a convenient embodiment of my invention is shown,

Fig. 1 is a vertical section showing the jacquard having my invention applied thereto,

Fig. 2 is an enlarged detail section on line 2—2 of Fig. 1,

Fig. 3 is a horizontal section on line 3—3 of Fig. 1,

Fig. 4 is a detailed vertical section on line 4—4 of Fig. 1, and

Fig. 5 is an enlarged plan of a portion of one of the needles.

Referring to the drawings jacquard frame 10 has a needle board 11 through which projects a plurality of needles 12 which are arranged in parallel horizontal planes. The left ends of the needles are guided by a

fixed vertical pin 13 mounted on a spring box 14 and springs 15 normally hold the needles to the right as viewed in Fig. 1. The cylinder 16 receives the usual cards one of which is indicated at 17, said cards having perforations and blank spaces to cooperate with the needles and leave the same at rest or push them to inoperative position, as the case may be.

A griff frame 18 receives vertical reciprocating movement by mechanism not shown, causing the knives 19 to lift those jacks 20 the needles of which are opposite holes in the card 17. The jacks or hooks 20 control the vertical position of the warp threads to determine the pattern of the fabric being woven. The cylinder and a new card will be moved toward the needles each pick of the loom and while the cylinder is adjacent the needle board 11 the griff frame will move upwardly, thus forming the shed for the shuttle. The matter thus far described is of common construction and forms no part of my present invention.

My improvements relate to the form of connection between the needles and the jacks. As previously stated it is old to make a loop in the needle through which the jack passes and it is also old to form the needle with an open eye in the form of an arc somewhat less than 180° in which the jack lies. Both forms of eyes are objectionable in a fine index jacquard, the closed eye taking up too much room and the open eyes giving an undesirable lateral movement to the jacks.

The form of eye which I employ is shown more particularly in Figs. 2 and 5 where it will be seen that the needle is provided with a crimp or eye 30 which is partly but not entirely closed, this eye being of such size as to receive the corresponding jack 20. As shown in Fig. 2 the open part of the eye receives the rounded part of the adjacent eye, thus permitting close assembly. It will also be seen that the opening of the eye is slightly less than the diameter of the jack 20 so that the latter is held positively against undue lateral displacement. Fig. 4 shows how close the various parts of a fine index jacquard are to each other and why it is necessary to keep these parts in proper position.

From the foregoing it will be seen that I have provided a jacquard needle having a partly closed eye of such size and propor-

tions as to permit close nesting of the needles and at the same time prevent undue lateral movement of the jacks. The arc of the needle eyes is somewhat more than 180° and less than 360° . I find that a jacquard made as set forth herein will accommodate a large number of needles without spreading the jacks over too large an area.

Having thus described my invention, it will be apparent that changes and modifications may be made therein by those skilled in the art without departing from the spirit and scope of the invention and I do not wish to be limited to the details herein disclosed but what I claim is:

1. In a jacquard mechanism, a plurality of warp controlling jacks, a needle to control each jack, and an open eye formed in each needle and surrounding a portion of the jack, said eyes having openings of less width than the diameter of the jack to restrain lateral movement of the latter and a portion of one eye lying opposite an opening in an adjacent eye.
2. In a jacquard mechanism, a plurality of warp controlling jacks, a needle to control each jack, and an open eye formed in each needle and extending around the greater part of the corresponding jack to restrain lateral movement of the latter and a portion of one eye lying opposite an opening in an adjacent eye.
3. In a jacquard mechanism, a plurality of warp controlling jacks, a needle to control each jack, and an open eye in each

needle surrounding a portion of the corresponding jack, the arc of the eye being greater than 180° and less than 360° a portion of one eye lying opposite the open part of the adjacent eye.

40

4. A jacquard needle having an open eye therein the arc of which is greater than 180° and less than 360° the opening being formed at the side of the eye and between longitudinally extended parts of the needle and being substantially aligned with the point of maximum lateral projection of said eye from the axis of said needle.

45

5. A jacquard needle having an eye open on one side and having the arc of the interior of the eye greater than a half circle the opening being formed at the side of the eye and between longitudinally extended parts of the needle and being substantially aligned with the point of maximum lateral projection of said eye from the axis of said needle.

50

6. A jacquard needle formed of wire and having an eye therein made by bending the wire so that the bend lies in the plane of the wire, said eye having an opening at the side thereof and between longitudinally extended parts of the needle, which opening is of less width than the greatest internal diameter of the eye and is substantially aligned with the point of maximum lateral projection of said eye from the axis of said needle.

55

In testimony whereof I have hereunto affixed my signature.

THOMAS KELLEY.
